TRAILER

Alton L. Lindig, Houston, Tex.

Application March 12, 1947, Serial No. 137,546

Term of patent 14 years

(Cl. D14—3)

To all whom it may concern:

Be it known that I, Alton L. Lindig, a citizen of the United States, residing at Houston, in the county of Harris and State of Texas, have invented a new, original, and ornamental Design for a Trailer, of which the following is a specification, reference being made to the accompanying drawings, forming a part thereof, in which said drawings the dotted lines are used for illustrative purposes only.

The drawings show only one side elevation of my design; the opposite side elevation having the appearance of the side elevation disclosed with the exceptions that the stairs or steps and also the window are omitted from this opposite side.

Fig. 1 is a side elevational view of the trailer showing my new design;

Fig. 2 is a plan view of the trailer taken on line 2—2 in Fig. 1;

Fig. 3 is a front elevational view taken on line 3—3 in Fig. 1;

Fig. 4 is a rear elevational view taken on line 4—4 in Fig. 1.

I claim:

The ornamental design for a trailer, substantially as shown and described.

ALTON L. LINDIG.
